UNITED STATES PATENT OFFICE.

ARTHUR GORDON, OF WINTerset, IOWA.

DESIGN FOR A SIGNBOARD.

Application filed December 2, 1927. Serial No. 24,367. Term of patent 7 years.

To all whom it may concern:

Be it known that I, ARTHUR GORDON, a citizen of the United States of America, residing at Winterset, in the county of Madison and State of Iowa, have invented a new, original, and ornamental Design for a Signboard, of which the following is a specification, reference being had to the accompanying drawing, which forms a part thereof.

I claim:

The ornamental design for a signboard, as shown.

ARTHUR GORDON.
